UNITED STATES PATENT OFFICE.

FREDERICK COTTERELL, OF MELBOURNE, VICTORIA, AUSTRALIA.

GLASS-POLISHING MACHINE.

1,302,316.

Specification of Letters Patent.

Patented Apr. 29, 1919.

Application filed April 26, 1917. Serial No. 185,963.

To all whom it may concern:

Be it known that I, FREDERICK COTTERELL, a subject of the King of Great Britain and Ireland, residing at 35 Lonsdale street, Melbourne, in the county of Bourke, State of Victoria, Commonwealth of Australia, have invented new and useful Improvements in Glass-Polishing Machines, of which the following is a specification.

10 My present improvements in glass polishing machines relate essentially to,

Firstly. The provision of two hinged tables, provided each with means for elevating and adjusting them to the same angle, but in 15 opposite directions, whereby the beveled edges of two sheets of plate glass of equal or of different widths or thickness can be readily placed at the same level and polished simultaneously in one operation; or for allowing said tables to be set horizontally and then adjusted to occupy any position beneath the rotating polishers, whenever used in the polishing of flat surfaces.

Secondly. The employment of slideable 25 geared base plates and geared supporting and extension rails positioned in guide beds for carrying said tables, when occupying any position during the polishing of either beveled edges or flat surfaces.

30 Thirdly. Adjusting means for setting one of said tables to the precise angle so that the beveled edges, prior to polishing, can be made truly level with each other whenever the sheets of glass are not of the same thickness.

Fourthly. The shape and arrangement of the rotating polishers acting in concert together for use in flat surfaces of plate glass, whereby a greater amount of surface can be 40 polished in one operation than by the use of plain circular rotating polishing disks.

Fifthly. Means for feeding the polishing material to the center of the polishing faces of the rotating polishers so that they will be 45 always "wet" while polishing the beveled edges, or flat surfaces of sheets of plate glass.

The invention will be better understood upon reference to the several figures of the

accompanying sheet of drawings which are 50 to be read with this specification.

Figure 1 is a front elevation of my improved glass beveling machine, while Fig. 2 is a plan of same. In these figures, the position of the alternately arranged right and left rotating polishers are shown either by vertical or circular dotted lines situated above said tables.

Fig. 3 is an end elevation of machine, showing the relative positions of said adjustable tables when horizontally arranged or set at the inclined positions shown by dotted lines. This figure further illustrates a sectional view of a rotating polisher, and operating gear employed therefor, but without 60 the end supporting pedestals.

Fig. 4 is a partial longitudinal elevation of adjusting means shown at Fig. 3 for setting one of said tables to the precise angle 65 for the purpose hereinbefore indicated.

Fig. 5 is an end sectional detail view of 70 two of the geared and supporting extension rails as also one of the two toothed racks attached one to the outer rail of each pair.

Fig. 6 is a front elevation of the hand 75 lever gear, as also of the form of bracket employed in connection with each rotating polisher.

Fig. 7 is a view of the bracket shown in Fig. 6.

Fig. 8 is a sectional plan of said bracket taken upon the line A, B, Fig. 7, showing also a portion of a slideable carrier positioned in front thereof, while Fig. 9 is an elevation of one end of said slideable carrier.

Fig. 10 is a sectional plan of said bracket taken upon the line C, D, Fig. 7.

Fig. 11 is a partial elevation of a plain disk rotating polisher employed for beveled edges of plate glass, showing in dotted lines 90 the means for feeding the polishing material to the flat surfaces of plate glass.

Fig. 12 is a plan of three of the rotating polishers, acting in concert together, specially designed for polishing a large surface 95 of plate glass at one operation.

Fig. 13 is a part elevation of one of said rotating polishers shown at Fig. 12.

Fig. 14 is an end elevation of the operating gear, showing its connection with the reciprocating frame illustrated in Figs. 1, and 2.

5 Like numerals refer to like parts in all the views.

In the drawings, it will be seen that the machine consists essentially of two side frames (1) and (2) arranged parallel with 10 each other, and supported in an upright position by means of the five transverse stays (3). Said frames are specially designed with means which allow of the support and adjustment of the two tables (4) 15 and (5), each of different width.

The table (4) serves for carrying wide sheets of plate glass, and the other (5) for narrow sheets. These two tables are adapted to be so adjusted as to occupy oppositely 20 inclined positions, as shown by dotted lines Fig. 3, when beveled edges are to be polished; or they may be adjusted to a horizontal position, to allow of the polishing of flat surfaces only.

25 The table (4) is hinged to, and carried by two double brackets (6) by means of pins passed through eyes of two lugs (7) projected from underpart of table; and an eye in each of said brackets.

30 The other table (5) is carried by the cam spindle (8) projected through two bearing blocks (8^a) also provided upon the underpart, while the reduced end portions (8^b) and (9) of said spindle (8) are passed 35 through eyes which are also provided in said brackets (6) secured to, and carried by the sliding base plates (10) and (11) respectively. Said tables (4) and (5) are arranged so that there will always be a clear-

40 ance or parallel opening or space between their inner edges, as at Fig. 3, and so that they can be adjustably positioned beneath said rotating polishers, by the use of toothed side racks (12) and (13) removably se- 45 cured to the outer face of the rails (15) and (17) so as to be engaged by pinions (18) and (19) carried by the horizontal spindle (20).

Two pairs of brackets (22) and (23) are 50 securely attached to the end portions of said sliding base plates (10) and (11). One pair of such brackets (22) has tubular shaped bearings (24) and (25) projected outwardly therefrom to carry said horizontally arranged spindle (20) provided with the hand operating wheel (21). Each pair of said angle brackets carry two horizontal pinion shafts hereinafter described, and also stays (25^a) and (23^a) which serve with 55 said sliding base plates (10) and (11) to comprise a slideable frame.

For the support and adjustment of the tables (4) and (5) I provide the four double flanged extension rails (14), (15), (16)

and (17), arranged in pairs, each pair consisting of one "inner" and one "outer" rail, which are specially constructed to be slidably operated in the guide beds (26) and (27) of said frames (1) and (2), and so that their top surfaces will serve, first. As 65 a guideway for the two sliding base plates (10) and (11) carrying the two beforementioned double brackets (6). And second, as a means whereby the inner slideable rails (14) and (16) can be projected outwardly 70 to provide an extended support for said tables (4) and (5) during the operation of polishing flat surfaces. Each pair of rails is slidably positioned with their machined vertical faces, engaging each other, and slidably kept in position in the guide beds (26) and (27) by four flanged guide caps (28), (29), (30) and (30^a) removably secured to the outer faces thereof. These slideable rails have inset toothed racks (31), (32), (33) 80 and (34) situated one in the underpart of each rail as shown at Fig. 3. (35) and (36) are two horizontal operating spindles suitably positioned in bearings (37) of frames 1 and 2; the spindle (36) is provided with 85 the hand operating wheel (38), and also two pinion wheels (39) and (40) operating with the other pinions in recessed portions (41) and (42) of said frames 1 and 2.

These pinion wheels (39) and (40) engage the toothed racks (32) and (33) of the inner rails (14) and (16) respectively; while the two outer positioned pinion wheels (43) and (44), carried by said spindle (36), engage the other pinion wheels 100 (45) and (46) of spindle (35) for operating the outer toothed racks (31) and (34) of the outer rails (15) and (17).

It will be observed that the two inset toothed racks (32) and (33) differ in situation, and also in length, from the other two racks (31) and (34); the object being to allow the inner rails (14) and (16) to be extended in one direction for supporting the wide table (4) when employed under 105 the rotating polishers in the polishing of flat surfaces, as well as to allow the outer rails (15) and (17) to be moved in the opposite direction when the narrow table (5) is likewise used beneath said rotating polishers. (47) and (48) are V shaped guides provided one upon each of said rails (15) and (16), to engage the inverted V shaped grooves (49) and (50) adaptably situated in the bottom part of the slideable base plates 110 (10) and (11) to the extent of the full length of the latter, whereby the tables will always be guided to slide in a horizontal plane.

The means for setting the narrow table 125 (5) so that it will occupy the precise angle to allow of the beveled edges being arranged exactly level with each other when the sheets

out actual contact as the proper setting of the worm wheels (89) and worm pinions (88) in their respective positions enables such an arrangement to be carried out.

5 The means for feeding the polishing material to the surfaces to be polished comprise the annular channel or gutter (112) situate concentric with the circumference of spindle (91). Communicating with this 10 gutter and the face of rotating polishers are two passage ways (113) situated at an angle toward the vertical axis of said spindle (91) so as to allow the polishing material to exude or flow centrally to the polishing faces 15 and on to the surfaces while being polished, so that the rotating polishers will be always what I term "wet".

The operation of my machine is as follows:—

20 When motion is imparted to the belt pulley (84), spindle (83), and worm pinion (82) the worm wheel (76) operates the connecting rod (79) so as to reciprocate the frame (73). The driving shaft (86), belt 25 driving pulley (87^a), bearings (85), as also the rotating polishers, all move with said reciprocating frame.

Although said frame has imparted to it a reciprocating movement, the worm pinions 30 (88) operate the worm wheels (89) of spindles (91) of rotating polishers, which revolve at any desired speed.

The adjustment of either the wide or narrow tables (4) and (5) to a position beneath 35 the rotating polishers is effected by operating the hand wheel (21) and spindle (20), so that the pinions (18) and (19) will engage the toothed side racks (12) and (13) of the sliding rails (15) and (17). When 40 flat surfaces are to be polished the tables (4) and (5) and extension rails are slid by turning the wheel (38), and shafts (35) and (36) so as to rotate the pinions (39) and (40) for moving the inner rails (14) and 45 (16) in one direction outwardly from the rotating polishers; while the other geared pinions (45) and (46) engage the toothed racks (31) and (34) and operate the outer rails (15) and (17) in the opposite direction 50 so that a bed equal to the width of the combined tables will be provided.

There is therefore, in each pair of projected rails, one of such rails engaging the respective guideways (49) and (50) of sliding base plates (10) and (11) with the guides (47) and (48), thereby allowing of the tables being always supported and guided in a straight line. Said tables (4) and (5) may be adjusted to lie horizontally, 60 or at any desired angle, by operating the hand wheels (72) and spindles (69), so that the worm wheels (67) engaged by the worm pinions (68) will rotate the shafts (63) and (64). The rotation then given to said 65 shafts imparts a vertical movement to the

toothed racks (56), (57), (58) and (59) geared with the pinion teeth of shafts, either upwardly or downwardly, as the case may be.

The pressure required for polishing the 70 beveled edges is obtained by utilizing the weight of the rotating polishers, the hand lever gear and its attached parts; or if desired additional removable weights may be applied to the upper end portion of said 75 spindles (91).

Upon oscillating the bell crank levers (102) and (103) to a vertical position, the rotating polishers will be in the polishing position, but when horizontally placed the 80 polishers will be lifted up clear of the beveled edges or flat surfaces, in which case, the links (96) and (97) will remain in a disengaged position until again required for polishing.

85 The rotating polishers shown at Figs. 12 and 13 rotate with their arms (110) and (111) occupying the concavities in either side of adjacent polishers, thereby allowing them to operate with their centers closer together and at the same time relatively provide a greater amount of polished surface than would be possible with the use of circular or full diameter disks.

90 I wish it to be here understood that I do not lay claim to any part of the operating means shown for reciprocating the frame (73); nor to the parts comprising the hand lever gear; or the method of operating the right and left hand rotating polishers, but 95 what I desire to claim is:—

1. In a glass polishing machine having side frames, guide beds in said side frames, 100 slideable extension rails arranged in said guide beds, adjustable sliding base plates positioned upon said rails, brackets secured to said base plates and a pair of adjustable tables hinged to and carried by said brackets, one of said tables being of greater width than the other, a rotatable shaft for each 110 table, said shafts being provided with pinion teeth and a worm wheel, vertically disposed toothed racks meshing with said teeth, a rotating spindle having a worm pinion in mesh with said worm wheel, and a hand operating wheel on said spindle.

115 2. In a glass polishing machine having side frames, guide beds in said side frames, slideable extension rails positioned in pairs, in said guide beds, and provided each with an inset toothed rack, the inner rails having each rack differently situated to those of the outer rails, in combination with two operating spindles adaptably supported in bearings in said frame, and provided with pinions meshing with said racks whereby said inner rails will move in the opposite direction to the outer rails when said spindles are operated.

120 3. In a glass polishing machine, brackets 125

- of plate glass are of different thickness, consist of the beforementioned cam spindle (8) adjustably operated in said bearing blocks (8^a) by the handle (51) of a rod shown coupled with the reduced end portion (8^b). The handle is adaptably arranged so that it can be freed or securely clamped in position to the quadrant (52) by means of a thumb nut (53) provided 10 upon the outer screw threaded end portion of a pin (54) carried by said handle (51) and passed through a curved slot (55) of said quadrant (52) securely attached to end of table (5).
- 15 The adjustment of said wide and narrow tables (4) and (5) of my machine to an inclined or horizontal position can be effected by the employment of four vertically disposed elevating toothed racks (56), (57), (58) and (59) hinged to, and dependent from the four pins (60) situated in eyes of the ears or lugs (61) projected from the underside of tables. These toothed racks are each alike in construction and engage 20 pinion teeth (62) provided in and around the pinion shafts (63) and (64) arranged one for each table of machine, and adaptably supported in bearings provided in the beforementioned angle brackets (22) securely fixed to the sliding base plates (10) and (11).
- 25 Rollers (65), free to rotate upon axle (66) projected from each pair of the angle brackets (22) and (23), are adaptably arranged to engage the outer face of each toothed rack (56), (57), (58) and (59), and keep such racks permanently geared with the pinion teeth (62) of shafts (63) and (64).
- 30 In order to adjust or elevate the tables (4) and (5) the shafts (63) and (64) are provided with a worm wheel (67) which is engaged by a worm pinion (68) secured upon spindle (69) projected through the bearing (70) of central brackets (71) and provided with the hand operating wheel (72). The means employed for reciprocating said frame (73) in the guide beds positioned upon the top of the supporting pedestals (74) and (75) consist of the worm wheel (76) rotatably mounted upon the axle (77) projected from bracket (78) which is removably secured to top of the pedestal (75), connecting rod (79) coupled with crank pin (80) projected from one face of said worm wheel (76), and the pin (81) projected from the inner face of reciprocating frame (73) the worm pinion (82) geared with said worm wheel (76), and secured 35 upon the inner end portion of the rotating spindle (83) situated in bearing (70) of said bracket (77), and also belt driven pulley (84).
- 40 Upon the top face of said reciprocating frame are secured the bearings (85) to carry the horizontal rotating shaft (86) having collars (87) to prevent lateral movement; and also a belt driven pulley (87^a). This shaft carries right and left hand worm pinions (88), as at Fig. 3, alternately positioned and adapted to gear with and rotate the vertically arranged worm wheels (89) provided one upon each vertical spindle (91) which may be of sufficient length to allow of the upper end portions being provided with removable weights whereby additional pressure may be applied to the surfaces to be polished.
- 45 To the flat vertical face of said reciprocating frame (73) are securely attached a 80 number of brackets (90), as at Figs. 3, 6 and 7, one for each spindle of rotating polisher. These brackets (90) have each upper and lower tubular bearings (92) and (93), in which the spindle (91) is slidably 85 positioned so that it may, while rotating, be lifted up from, or lowered to the polishing position.
- 50 To provide for this upward or downward movement of said spindles I secure to each 90 one, a cross head (94) having two projected end pins (95) which pass through eyes provided in the upper ends of the links (96) and (97) hereinafter described and also through sliding blocks (98) and (99) positioned to engage the two guide faces (100) of brackets (90); while the lower ends of said links (96) and (97), forming part of the hand gear beforementioned, and pivotally connected with the two arms (101) of 100 the bell crank levers (102) and (103). These levers are fulcrumed upon the pin (104) having its ends projected through the eye of an ear or lug (105) situated upon tubular bearing (93); their outer ends being coupled together by means of the handle bar (106).
- 55 At the angle or heel portion of said bell crank levers are two lugs (107), to carry the cross bar (108) which bears or rests 110 against the tubular bearing (93) while such levers are holding up each spindle (91) and worm wheel (89) engaging the worm pinion (88) of the horizontal driving shaft (86), as shown at Fig. (3).
- 60 The rotating polishers may be either one of two designs, viz; plain rotatable disks as at Fig. 11 for polishing beveled edges; or they may be, comprised of two arms or blades (110), and (111) oppositely situated 115 to each other and projected from a boss having a central eye internally screw-threaded to engage the screw threaded lower end portion of spindle (91) as at Figs. 12 and 13. Between these arms or blades are concave sides; their outer end portions being rounded. Such polishers are adapted to 120 rotate independently of each other with-

Upon the top face of said reciprocating

and supports for said brackets, a pair of adjustable tables hinged to and carried by said brackets, bearing blocks projecting from the underpart of one of said tables, 5 a cam spindle situated in the bearing blocks, a quadrant mounted upon one end of said last mentioned table and formed with a curved slot, a handle fixed to said spindle and provided with a pin projecting through

said slot, whereby said table can be given 10 the desired angle so that the beveled edges of plate glass, of the same or of different thickness, may be readily made level with each other.

FREDERICK COTTERELL.
